(57) **CLAIM**

The ornamental design for a light fixture sensor as shown and described.

DESCRIPTION

FIG. 1 is a perspective view of a light fixture sensor in a light fixture showing our new design.

FIG. 2 is a perspective view of a light fixture sensor.

FIG. 3 is a side elevational view of FIG. 2.

FIG. 4 is a top elevational view of FIG. 2.

FIG. 5 is a side elevational view of FIG. 2.

FIG. 6 is an additional side elevational view of FIG. 2.

FIG. 7 is a bottom elevational view of FIG. 2.

FIG. 8 is a perspective view of a light fixture sensor in a light fixture showing our new design.

FIG. 9 is a perspective view of a light fixture sensor.

FIG. 10 is a side elevational view of FIG. 9.

FIG. 11 is a top elevational view of FIG. 9.

FIG. 12 is a side elevational view of FIG. 9.

FIG. 13 is an additional side elevational view of FIG. 9; and, FIG. 14 is a bottom elevational view of FIG. 9.

The broken line showing is included for the purpose of illustrating portions of the “article” and forms no part of the claimed design.
